UNITED STATES PATENT OFFICE.

MIKE DYKAS, OF CHICAGO, ILLINOIS.

DESIGN FOR A HORSE-COLLAR.

59,826.

Specification for Design.

Patented Nov. 29, 1921.

Application filed May 31, 1921. Serial No. 473,917. Term of patent 7 years.

To all whom it may concern:

Be it known that I, MIKE DYKAS, a citizen of Poland, residing at Chicago, in the county of Cook and State of Illinois, have invented a new, original, and ornamental Design for a Horse-Collar, of which the following is a specification, reference being had to the accompanying drawing, forming part thereof.

Fig. 2 is a side elevational view thereof.

I claim:

The ornamental design for a horse collar, as shown.

MIKE ^{his} ~~×~~ DYKAS.
